UNITED STATES PATENT OFFICE.

ANDREW J. CALLAGHAN, OF JACKSON, MICHIGAN.

VALVE.

1,106,488.

Specification of Letters Patent. Patented Aug. 11, 1914.

Application filed April 18, 1912. Serial No. 691,615.

To all whom it may concern:

Be it known that I, ANDREW J. CALLAGHAN, a citizen of the United States of America, residing at Jackson, in the county of Jackson and State of Michigan, have invented certain new and useful Improvements in Valves, of which the following is a specification, reference being had therein to the accompanying drawings.

10 The invention relates generally to improvements in valves designed primarily for use in connection with liquid transporting vessels, as barrels, tank cars and similar containers, and consists in the valve construction, in the arrangement and combination of parts, and in various details of construction as will be more fully hereinafter set forth.

In the drawings.—Figure 1 is a vertical central section through an embodiment of 20 my invention; Fig. 2 is a front elevation; Fig. 3 is a view in perspective of the parts detached; Fig. 4 is a detail sectional view of the shell sections; and Fig. 5 is a fragmentary side elevation of the inner shell section.

25 For the purpose of illustration, I have shown the structure in the form of a valved bung applicable to the ordinary keg or barrel.

The reference-letter A designates a container having the usual bung opening, in which is fitted a metallic bushing B threaded both exteriorly and internally as shown. Inserted within the bushing is the valve structure C, externally threaded as at D to 35 engage the bushing thread.

In general construction, it comprises complementary ported shell sections held one within the other for relative movement, the shells being provided with means for engaging the same with the receptacle to which they are applied, and with means for effecting their relative rotation to shift the ports into or out of registration.

40 E represents the outer shell member, formed at its outer end with a hexagonal section F, constituting the wrench-hold, by means of which the shell is engaged within the bushing. At its opposite end this section is headed, as at G, and the head is centrally apertured as at H and provided with an elongated port I.

J is the inner shell section fitted within the outer for rotary movement. Its outer end is provided with a wrench-hold K, affording 55 means for effecting the rotation, and its inner end with a head L adapted to seat

against the head G of the outer section. The inner shell head is provided with a port M corresponding in size and form and adapted to register with the port I, and with a central pin O which projects through and beyond the opening in the outer member or section.

To hold the head sections of the members in contact, a spring P is employed encircling 60 the stem O, bearing at one end against a washer Q held upon the stem against rotary movement, and at the opposite end against lock-nuts R.

As shown in Fig. 1, the ports are in registration, which allow the discharge of the receptacle contents. Upon the rotation of the inner shell section, these ports are brought out of registration, and the opening in the receptacle is closed. It is adapted for use 70 either as a valved bung, as set forth, or the valve may form part of a connection leading from the container to a distant point, the inner section in this instance constituting a coupling. For this latter purpose the interior of the inner shell section is threaded as at S to receive the threaded end S¹ of the conduits S², and as so constructed the device is particularly useful in that if any 75 break occurs in the conduit or piping leading from the container the discharge may be immediately shut off by a rotation of the inner shell section, allowing the repair to be made without loss of contents.

80 In the form illustrated, the device is particularly useful in connection with tank cars, and when thus employed I may and preferably do apply a cap to the outer end of the fitting to protect the extremity of the valve mechanism and prevent accidental turning. 90 This cap may be of the form shown, indicated by the letter T, and is adapted to engage the thread S upon the inner shell section. Preferably a chain T' is provided for preventing the cap from becoming lost when 95 removed. I also preferably provide one of the sections with a lug or pin which is adapted to engage shoulders or bearings on the other section.

100 As shown U is a pin projecting laterally from the outer face of the hexagonal portion on the outer shell member and V is a cut-away portion in the under face of the wrench-hold K providing spaced bearings or shoulders W and X for engaging the pin 105 U and arresting relative movement between the shells in both the opening and closing

of the valve. During the opening of the valve the inner shell is turned to the left until the pin U strikes the bearing W, and in this position of the shells the bores I and M are in registration. To move the bores out of alinement the member J is turned to the right and after the bores pass out of registration the pin engages the shoulder X. In this latter relation of the parts the 10 hexagonal portions of the inner and outer shells register forming a wide wrench-hold. The pin U and shoulders not only serve to properly position the bores I and M in and out of alinement, but the shoulder X 15 operates with the pin to prevent accidental opening of the valve during the engaging of the latter with the barrel or other receptacle. Thus, in applying the valve to the usual bung opening of the barrel or the like, 20 if the wrench was accidentally engaged with only the part K, there would be a tendency to turn the inner shell relative to the outer. But, as before stated, in the closed position of the valve, rotation of the inner shell to 25 the right is prevented, it being understood, of course, that the exterior of the outer shell has right hand threads.

What I claim as my invention is,—

1. In a valve mechanism, the combination 30 with an outer shell section adapted for insertion within the discharge opening of a container, of an inner shell section rotatable within the outer, said sections having heads provided with ports adapted to be brought 35 into and out of alinement upon the rotation of the inner shell, and means for maintaining said heads in contact, said shells having polygonal wrench engaging portions adapted 40 to aline.

2. In a valve mechanism, the combination 45 with an outer shell section adapted for insertion within the discharge opening of a container, of an inner shell section rotatable within the outer, said sections being provided with ports adapted to be brought into 50 and out of alinement upon rotation of the inner shell, and means for securing the inner

shell within the outer, said shells having wrench engaging portions adapted to aline, for the purpose described. 50

3. In a valve mechanism, the combination with an outer headed shell section adapted for insertion within the discharge opening of a container, of an inner headed shell section rotatable within the outer, means for 55 maintaining the heads of said section in contact, said shells being provided with ports adapted to be brought into and out of alinement upon the rotation of the inner shell and having wrench engaging portions adapted 60 to aline, for the purpose described.

4. In a valve mechanism, the combination with an outer shell section adapted for insertion within the discharge opening of a container, of an inner shell section rotatable 65 within the outer, said sections having ports adapted to be brought into and out of alinement upon the rotation of the inner section, means for maintaining said section in engagement, and means for arresting movement of the inner section in one direction, 70 said sections having polygonal wrench engaging portions alining when the inner section is in said arrested position.

5. In a valve mechanism, the combination 75 with an outer headed shell section adapted for insertion within the discharge opening of a container, of an inner headed shell section rotatable within the outer, said sections being provided with ports adapted to be 80 brought into and out of alinement upon the rotation of the inner section, means for maintaining the heads of said sections in contact, the inner section being internally threaded, and a cap member having a portion engaging said internal threads and closing the inner section and having a portion 85 engaging the outer.

In testimony whereof I affix my signature in presence of two witnesses.

ANDREW J. CALLAGHAN.
